(57) **CLAIM**

The ornamental design for a snap button, as shown and described.

DESCRIPTION

FIG. 1 is a front, top perspective view of a snap button, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, top perspective exploded view of the snap button; and,

FIG. 10 is a rear, bottom perspective exploded view thereof. The broken lines in the figures illustrate portions of the snap button that form no part of the claimed design.
